CLAIM

The ornamental design for a centrifuge bottle, as shown and described.

DESCRIPTION

FIG. 1 is an isometric view of a centrifuge bottle of my new design;

FIG. 2 is a front elevation view of the centrifuge bottle of FIG. 1, the rear view being identical thereto;

FIG. 3 is a side elevation view of the centrifuge bottle of FIG. 1, the other side view being identical thereto;

FIG. 4 is a top elevation view of the centrifuge bottle of FIG. 1; and,

FIG. 5 is a bottom elevation view of the centrifuge bottle of FIG. 1.

(Continued)

The centrifuge bottle is shown with symbolic breaks in its length. The appearance of any portion of the article between the break lines forms no part of the claimed design.
